UNITED STATES PATENT OFFICE.

JOHN G. LARSON, OF OAKLAND, CALIFORNIA.

BOOK-RACK

1,245,111.

Specification of Letters Patent.

Patented Oct. 30, 1917.

Application filed December 1, 1913. Serial No. 803,939.

To all whom it may concern:

Be it known that I, JOHN G. LARSON, a citizen of the United States, residing at Oakland, in the county of Alameda and State of California, have invented certain new and useful Improvements in Book-Racks, of which the following is a specification.

This invention relates to book holders and more particularly to a device for supporting loose leaf ledgers and the like, so that the pages thereof present a flat writing surface, on a level with a stationary arm rest.

The principal object of my invention is to provide a support for the purpose set forth, having two flexibly connected back rests, so supported that they automatically adjust themselves to bring the writing surface level with the arm rest no matter at what page the book is opened.

Another object is to provide means for changing the length of the said flexible connection so as to take care of various sized books.

With these and other objects in view my invention consists in the new and novel construction and arrangement of parts as hereinafter described and illustrated in the accompanying drawings, and as more specifically pointed out in the claims hereunto annexed.

Referring to the attached drawing forming a part of this specification,

Figure 1 is a view in plan of my improved device showing the same without a book thereon.

Fig. 2 is a view in section on 2—2 Fig. 1 showing in outline an open book positioned thereon.

Fig. 3 is a view in section on 3—3 Fig. 1.

Fig. 4 is a view in section on 4—4 Fig. 1.

Denoting corresponding parts by the same numerals of reference, 1 is a substantially rectangular frame having the end walls 2 front and rear walls 3 and 4 respectively. Intermediate 3 and 4 is a division wall 5 attached to the ends 2. Over the space 5' thus formed between division wall 5 and front wall 3 is placed an adjustable cover plate 6, which forms an arm rest.

The adjustment of this arm rest is effected by providing depending guides 7 adjacent each end of the rest, which fit closely within the rectangular cavity 5' and in these guides are provided angularly disposed slots 8. The end plates 2 are also slotted as at 9,

which slots are provided with circular serrations 10. The latter are of such size that a pin 11 is held therein against longitudinal movement. Thus to adjust the height of 60 the rest it is only necessary to raise the same to the required height and insert the pin 11 through the serration in alinement with the incline slot 8.

The rest for the book shown in dotted outlines at 12 consists of two flat plates 13 and 13' slidable on the inclined guide bars 14. As shown on the drawing I provide slots 15 in the end of plates 13 and 13' in which the bars 14 fit but if desired the plates may be 70 fitted with rollers which engage these bars thus making the movement of the plates easier.

The plates are connected by an inelastic flexible strip 17 the end being held fast to 75 plate 13 by a strip 16 nailed or screwed thereon while the other ends pass freely between the plate 13' and strip 16' secured thereon and are secured to a roller 18. This roller is pivotally mounted in bearings 19 80 and 19' and on one end is secured a toothed worm wheel 20.

A worm 21 meshing with the latter is revolvably mounted in extension of bearing 19' and the shaft thereof is provided with 85 a squared end, which extends into a hole in plate 13' rendering it accessible for adjustment from above.

In use the flexible strips 17 are adjusted until with the back of the book resting 90 thereon the covers lie flat on the plates 13 and 13'. Now when the book is opened near the front, plate 13 is depressed while 13' is correspondingly elevated causing the opposite pages to lie in a substantially horizontal plane. The arm rest can then be adjusted to give the greatest ease in writing on these pages.

As the pages are turned to the left plate 13' will be depressed causing the strip 17 to 100 pull plate 13 to the left. This force will in turn cause the latter plate to move upwardly and to the left along the guideways 14 of that plate. Even when plate 13' is below the level of plate 13, this same action 105 will take place until the portion of the strip 17 adjacent the plate 13 is at right angles to the inclination of the guideways, as until this position occurs there is a resultant force which tends to move the plate upwardly. 110 Thus as the plate 13' is depressed 13 is elevated so as to maintain the upper surfaces

of the pages of the book at approximately the same level.

From the foregoing description it will be seen that I have provided a simple and effective device, which accomplishes the objects hereinbefore set forth, and while I have shown the preferred embodiment of my invention it will be understood that minor changes may be made in form and detail 10 without departing from the spirit thereof.

What I claim as new and wish to cover by Letters Patent is:—

1. A book holder comprising a frame, a pair of plates for supporting covers of a book, means for slidably supporting said plates, and a flexible member connecting said plates to permit either plate to rise as the other is depressed by the weight of that portion of a book supported thereby.

20 2. A book holder comprising a frame, a pair of plates for supporting covers of a book, means for slidably supporting said plates to permit either plate to rise as the other is depressed by the weight of that portion of a book supported thereby, a flexible member connecting said plates and means for varying the effective length of said flexible connection.

3. A book holder comprising a frame, upwardly converging guideways, plates engaging said guideways forming rests for the respective book covers, and a flexible substantially inelastic connection between said plates, so that when the pages of said book 35 are turned one plate may be depressed while the other is moved upwardly.

4. A book holder comprising a frame, a pair of plates forming rests for the book covers, a plurality of parallel inclined 40 guides engaging opposite edges of each of

said plates, the guides of opposite plates being upwardly converging, flexible substantially inelastic strips connecting the adjacent edges of said plates, so that when either plate is depressed the other plate is 45 constrained to move upwardly along its guides, and means for varying the effective length of said strip.

5. A book holder comprising a frame, a pair of plates forming rests for the respective covers of a book, guides on which said plates are slidably mounted, the guides of opposite plates converging toward each other, adjustable flexible substantially inelastic strips connecting the inner edges of 55 said plates so that when either plate is depressed along one guide the other is constrained by said strips to move upwardly along the oppositely inclined guide.

6. A book holder comprising a frame, a pair of plates forming rests for the book covers, pairs of parallel inclined guides engaging opposite edges of each of said plates, the guides of opposite plates being upwardly converging, adjustable flexible substantially 65 inelastic strips connecting the adjacent edges of said plates, so that when either plate is depressed the other plate is constrained to move upwardly along its guides, a reel on the underside of one of said plates 70 to which said strips are attached, and means for turning said reel to vary the length of said strips.

In testimony whereof I affix my signature in presence of two witnesses.

JOHN G. LARSON.
